UNITED STATES PATENT OFFICE

2,021,802

RESISTANCE UNIT

John J. Mucher, Brooklyn, N. Y.

Application August 10, 1934, Serial No. 739,316

6 Claims. (Cl. 201—63)

This invention relates to resistance units, and has for an object to provide an improved construction wherein the parts are so constructed and arranged that there is no danger of breaking any of the resistance elements during the assembling of the device, the invention being an improvement over my co-pending application Serial No. 690,730, filed September 23, 1933, which issued as Patent 1,982,475, November 27, 1934.

10 Another object of the invention is to provide an improved construction wherein a continuous resistance element may be presented formed of wire or other material and any desired number of contacts taken therefrom, without endangering the proper functioning of the resistance element.

A still further object of the present invention is to provide a resistance unit wherein there is provided a terminal base with a number of terminal members, one or more independent resistive elements, insulating sheathing members, and a protecting and clamping metallic sheathing.

An additional object, more specifically, is to provide in a resistance unit a construction wherein the parts of the unit may be readily assembled without injuring any of the assembled elements.

In the accompanying drawing—

Figure 1 is a top plan view of a resistance unit disclosing an embodiment of the invention;

30 Figure 2 is a longitudinal, vertical, sectional view through Figure 1 on the line 2—2;

Figure 3 is a transverse sectional view through Figure 1 on the line 3—3;

35 Figure 4 is an inverted perspective view of the metal sheathing showing part of the walls unfolded and ready to receive certain of the other parts;

Figure 5 is a perspective view of the terminal base shown in section in Figure 2;

40 Figure 6 is a plan view of an insulating element adapted to insulate certain parts;

Figure 7 is a plan view on a reduced scale of the resistance element shown in Figure 2;

Figure 8 is a bottom plan view of a terminal base similar to that shown in Figure 5, but made appreciably longer;

Figure 9 is a plan view of a pair of resistance elements adapted to be used in connection with the terminal base shown in Figure 8;

50 Figure 10 is a perspective view similar to Figure 5 but showing a slightly modified structure.

Referring to the accompanying drawing by numerals, 1 indicates a metal sheathing or casing which is provided with a top 2 bent to form

55 side walls 3 and 4, said side walls being shown

as upstanding in Fig. 4. When the device is completed, however, these walls are bent to form bottom plates 5 and 6, which plates are flush with the end tabs 7 and 8, said end tabs being formed from the respective end extensions 9 and 10 projecting from the top 2.

In forming the metal casing or sheathing 1 slots or openings 11, 12 and 13 are provided, as well as openings 14 and 15. Openings 14 and 15 are adapted to receive screws and other means 10 for clamping the resistance unit in position when in use, as illustrated in Fig. 2. The openings 11 to 13, inclusive, are intended to accommodate the respective terminals 16, 17 and 18. The openings just mentioned are sufficiently large to permit 15 these terminals to project through without contacting with the casing 1, the insulating sheathing 19 acting to hold the parts separated. As shown in Fig. 6 the sheathing 19 is provided with apertures 20, 21 and 22 to accommodate the various terminals, said apertures being of a size to permit the terminals to have a rather tight sliding fit whereby the terminals are spaced from the casing 1, as illustrated particularly in Fig. 1.

It will be noted that the sheathing 19 has a 25 section 23 which acts as a top, end tabs 24 and 25 which cover the ends 9 and 10, and flaps 26 and 27 which wrap around the resistance unit 28 and the terminal base 29 when the parts are in proper operative position.

30 It will be noted that the various terminals 16, 17 and 18 are permanently connected to the terminal base 29, which base is preferably made from fiber or other desired insulating material which is comparatively strong but rather thin. As 35 shown in Fig. 5 the terminal 17 extends through a suitable opening 30 in the base 29. The terminal 17 merges into a transverse strip which is shown in Fig. 8, and which is bent around base 29 and forms clinching hooks or extensions 32 40 and 33. The end terminals 16 and 18 extend across the end of the base 29 but are otherwise identical with terminal 17 and associated parts, whereby there are provided proper contact plates 34 and 35 merging into the terminals 16 and 18. 45

It will be understood that the constructions shown in Figs. 5 and 8 are identical except that the base 29 in Fig. 8 is made longer than the base 25 in Fig. 5. This arrangement of lengthening the base is to take care of the end-to-end resistance elements 35 and 37, which elements may contact or may be spaced apart as long as the winding thereon engages the flange or contact plate 31.

It will be understood that the resistance ele- 55

ment may be provided with two parts, as shown in Fig. 9, or a greater number of parts, and the same idea carried out without departing from the spirit of the invention. In comparatively small 5 resistance units a single unit, for instance, unit 28, is utilized, the same extending from the terminal 16 to terminal 18, illustrated in Fig. 2. Where the resistance unit is longer, one or more additional elements may be used but at a point 10 where the various resistance units are arranged end to end there must be a flange or plate similar to plate 31 to contact with the wires of each resistance unit.

It is understood that in resistance units of the 15 kind disclosed, the wire on the fiber, bakelite or other plates 30 is very fine as, for instance, the diameter of a very thin hair. This wire is laid on the unit base 38 by machinery and the wires are very close together and very fine. When the 20 terminals are being applied to this fine wire in any desired way, as for instance, in the way shown in my co-pending application above mentioned, it has been found that quite often a sharp corner or edge terminal will break one or more 25 of the wires of the resistance element, and, consequently, when the unit is completed and tested it will be found to have an open circuit between certain terminals. Great difficulty has been experienced in securing by soldering, clamping or 30 otherwise mounting a terminal for electrical engagement with fine wires just mentioned. These difficulties have resulted in much loss, as it is not known that there is an open circuit until after the unit is completed. By providing the terminal base 29, as shown in Fig. 5, along the terminals thereof, these difficulties have been overcome and regardless of how fine the wire is, the completed unit almost invariably presents one hundred percent test.

40 When assembling the unit as shown in Figs. 1 and 2, the shell is formed until it appears as shown in Fig. 4. The insulating sheathing 19 is then taken and placed in the casing so that the various apertures 20 to 22 will register with the corresponding openings 11 to 13, inclusive, of the casing. The structure shown in Fig. 5 is then taken and the terminals inserted through the slots 20 to 22, and also through the openings 11 to 13, until the base 29 is pressing against the 45 top section 23 of sheathing 19. The resistance element 28 is then placed in position on top of the terminal unit 29, all the parts being inverted during the assembly. After the element 28 has been placed in position, the ends 24 and 25 are 50 bent to the desired position, and the flaps 26 and 27 swung over to the position shown in Fig. 3. The device is then placed in a machine and the parts 5 and 6 bent to their finished position as 55 illustrated in Fig. 3, said bending causing the parts to be firmly clamped together. The clamping action naturally acts against the insulating sheathing 19, which may be asbestos or other desired insulation more or less resilient. This will cause the pressure on the parts 5 and 6 to make 60 the resistance element 28 to be in a certain sense resiliently pressed against the flanges or contact plates 31, 34 and 35. In this way a good contact is formed with a number of turns of wire of the resistance element, without any sharp 65 corners or edges engaging the winding.

In Fig. 10 a slightly different structure is shown to that illustrated in Fig. 5. As illustrated in this figure the base 38 is of insulating material and is cut the proper length but not provided with 70 any apertures. The various terminals 39, 40 and

41 are each provided with a base flange 42 which is turned over the respective edges of the base 38 and pinched at the under surface so as to present clamping spurs or flanges 43 and 44. By clamping the base flange 42 as just described 5 the end terminals may be properly mounted and one or more intermediate terminals readily clamped in place at a desired point or points without the necessity of accurately providing a punched hole. As shown in Fig. 5 the distance 10 between terminals 17 and 18 is shorter than between 16 and 17. If it should be desired to provide a device of this kind with terminals equally spaced it would be necessary to make a new die 15 so as to punch the hole centrally of the base. In the structure shown in Fig. 10 if the intermediate terminal was to be positioned centrally it would not be necessary to provide a new die but merely to position the terminal centrally and then clamp the same in place. Also, if a special order should 20 be received for two or more intermediate terminals there would be no difficulty as the additional terminals could be quickly and easily clamped at the respective points on the base 38.

I claim:—

1. A resistance unit comprising a rectangular metallic casing formed with a plurality of apertures arranged in a straight line in one face, an insulating enclosure member arranged within the casing and provided with apertures registering 30 with the apertures in the casing, a terminal base fitting flatwise against said insulation, a pair of end terminals and an intermediate terminal arranged in a straight line and permanently connected with said terminal base and having portions extending through the respective apertures in said casing and said insulating enclosure member to a point exterior of said casing and portions extending transversely across said base, and a flat fixed resistance element of the same 40 size and shape as said terminal base fitting flatwise against said terminal base and engaging the portions of the terminals extending transversely across the terminal base.

2. A resistance unit including a rectangular 45 casing formed with a pair of foldable sides adapted to be folded over after the unit has been assembled, a rectangular terminal base having a plurality of terminal members positioned at spaced points along the base, a fixed resistance 50 element of approximately the same size and shape as said base fitting against said terminal base so as to contact with said terminals, and insulating means surrounding said terminal base and said resistance element, the folding sides of 55 said casing when in operative position acting to hold the parts together so there will be a desired contact between the resistance element and said terminals to secure good electrical contact continually.

3. In a resistance unit of the character described, a resistance element having a base and a wiring of resistance wire thereon extending from substantially one end of the base to the other, a terminal unit comprising a flat base of 65 insulating material adapted to fit flatwise against the resistance element, and not less than three terminals carried by said base at spaced points along its length, said terminals fitting against certain wires of said resistance element, and 70 means for holding the resistance element in contact in said terminal unit.

4. A resistance unit comprising a casing having a plurality of openings in one face, an insulating sheath fitting into said casing and pro- 75

- vided with an aperture for each of said openings, a terminal unit comprising a flat base of insulating material, a pair of end terminal members and at least one intermediate terminal member, said terminal unit fitting within said insulating sheathing and having the terminals extending through said apertures, each of said terminals having a base flange, and a plurality of resistance elements fitted flatwise against said terminal unit, the flange of one of the terminals bridging the abutting ends of two of the resistance elements, while the flanges of the other terminals engage the resistance element at the respective ends thereof.
5. A resistance unit including a casing formed with a pair of foldable sides adapted to be folded over after the unit has been assembled, a terminal base, a terminal member at each end of said base, each of said terminal members having a part clinched to said terminal base, an intermediate terminal member having a part clinched to said terminal base intermediate the ends of the terminal base, a resistance element fitted against said terminal base and contacting with said terminal members regardless of the position of said intermediate terminal member, and insulating means surrounding said terminal base and said resistance element, the foldable sides of said casing when in operative position acting to hold the parts together so that there will be a desired engagement between the resistance element and
6. In a resistance unit of the character described, a resistance element having a base and a wiring of resistance wire extending from substantially one end of the base to the other, a terminal unit positioned next to and in engagement with said resistance element and extending from one end to the other of said resistance element, said terminal unit comprising a base of insulating material having an aperture therein spaced from the ends, a plurality of terminals, each of said terminals having upstanding posts and a flanged base, one of said terminals extending through said aperture with the flanged base fitting flatwise against one surface of the base of the terminal unit, the other terminals being arranged at the ends of the base of the terminal unit with the respective flanged bases of said terminals fitting flatwise against one surface of the base of the terminal unit and also flatwise against certain wires of said resistance element all of said terminals having their flanged bases turned over the respective edges of said base of insulating material and clinched, and means for holding the resistance unit in contact with the terminal unit so that the circuit between any two of said terminals will be through part of said resistance element.

JOHN J. MUCHER. 30
